DOOR HOLDER OR LATCH

Harry W. Titus, Uniontown, Pa.

Application May 10, 1938, Serial No. 207,082

2 Claims. (Cl. 292—128)

The invention has for an object to provide a door holder simple in construction, easy of operation, and positive in its action. It is an important aim of the invention to present a novel structure in the mounting and encasing of elements of such a device, to the end that it may be rapidly and effectively assembled with a minimum liability of faulty action, and whereby it will be liable in a minimum degree to derangement by wear, or ordinary stresses of service, and particularly so that liability of derangement by accidents will be greatly minimized.

A further object is to provide a novel detent-operating spring and mounting.

Additional objects, advantages, and novel features of construction reside in the construction, arrangement, and combination of parts involved in the embodiment of the invention as herein disclosed, as will appear from the following description and accompanying drawing, wherein

Figure 1 is a perspective view showing the device in operative relation to a door;

Figure 2 is a vertical cross section of the device when in engaged position;

Figure 3 is a partial top plan;

Figure 4 is a vertical cross section of the device when in disengaged position, and showing a modified spring mounting.

Figure 5 is a side elevation partly in section of a modification adapted to be mounted on another plane than that of the floor.

Figure 6 is a detail inner elevation of the spring seat.

The embodiment of the invention here disclosed, as an example of its use and practical application comprises a base member 10 which is provided with a flange portion 11 from the center of which an annular internally threaded boss 12 is projected. Countersunk holes 13 are formed in the flange to permit firm attachment thereof to a floor by means of screws 14. The base 10 is a standard fitting in the plumbing trade.

A section of pipe forms a standard 15 threaded at one end and screwed into the boss 12. The upper end of the standard 15 is longitudinally slotted on the end as at 16, of sufficient width to accommodate a detent lever 17 of the first order and of sufficient depth, along the axis of the standard, to serve as a stop 18 for one arm of the lever at the one side and to have proper clearance and a lower stop for the other arm of

the lever, as at 19, on the other side of the standard.

The lever 17 is pivotally carried on a pin 20 journalled in the standard 15 so that the lever may oscillate in the plane of the slot.

The lever 17 is of the first order, one arm forming a working portion 21, the other 22 being useful in obtaining a turning moment when force is applied to it—either manual from above or spring-pressed from below.

The arm 21 of lever 17 is provided with a detent notch 23 in its lower side, and a cam surface 24 directed upwardly from the outer lower edge of the detent slot and outwardly from the pin 20, forming a hook or bill 25. The cam 24 is adapted to be engaged by the bight of a U-shaped loop 26 moving the lever upwardly so that the notch 23 may be in a position to engage the bight 26.

The arm 22 is provided with a stirrup or notch 28 at a suitable radius to permit the end of a spring 29 to rest therein. The spring 29 is a flat leaf spring extending longitudinally of the standard 15 and anchored at its lower end 30 to the inside of the standard.

As shown in Figure 4, the spring need not be apertured and the anchorage for the spring 29 may consist of a tongue 33 pressed inward from the wall of the standard 15, and arranged with an upper end part parallel to the original position of the material pressed from the wall to form the tongue. The end 30' of the spring is simply set under and against the tongue. The tongue is narrower than the spring which therefore may lie across the opening formed in the wall by displacement of the tongue material. The curvature of the wall of the standard prevents the spring from slipping laterally. As the spring is constantly under longitudinal compression it is thereby held in place without fastenings, and assembly will be simplified and labor economized. It will be seen in Figure 2 that the spring 29 is under strain at the engaged position as is shown by the curve therein. Thus, a considerable initial force or torque is produced tending to keep the detent securely in engaged position.

The arm 22 is initially inclined upwardly from the fulcrum 20 so that manual or pedal pressure may be readily applied without liability of slipping off when the lever moves. The gradient is toward the fulcrum rather than toward the end of the lever. The end of the arm is provided with a widened portion 32 to permit more ready application of force thereto.

The modification shown in Figure 5 comprises a lever 17' of modified design the parts of which corresponding to those of the lever 17 are indicated by similar numerals with a prime mark applied. It is mounted on the pin 20 in a standard 15' similar to that first described except that the slot under the arm 22' is deeper to the stop 19'. The lever 17' is constructed so that manual force may be applied to the lever 17' in a direction perpendicular to the axis of the standard 15', while the cam 24' and detent notch 23' are adapted to be operative with a fastening member 31 such as is shown in Fig. 1, moving substantially along the axis of standard 15'. This 15 form of the article is well adapted to be mounted on a wall or base board.

The automatic operation of the device may be seen in Figure 2 wherein the loop 26 and the arm 21 are shown by dotted lines in positions 20 involved as it moves to the right to its final engaged position. It first engages near the top of the cam face 24, raising the lever against the force of spring 29 until the loop passes the bill or edge of notch 23 and receives the bill therein. 25 Manual operation is shown in Figure 4 wherein the detent notch 23 has been raised from element 26 by foot pressure on the arm 22. The additional curve assumed by the spring in compliance with force acting with a resultant on a line between the extremity and base of the spring is 30 also apparent in Figure 4. However, the moment arm of this spring force is reduced due to the

rotation of the stirrup 28 more nearly to the line from fulcrum 29 to the opposite end of spring 29. This results in preventing an undue increase of load as the lever moves to disengaged position and permits a more substantial initial retaining force to be maintained than would otherwise be possible. 5

I claim:

1. A door holder comprising a footed base having an internally threaded annular boss, a tubular exteriorly threaded standard screwed therein at one end, said standard being longitudinally slotted on opposite sides at its opposite end, a lever pivoted in said slots constructed to engage and hold a door element at one position, the root 10 of said slot at the one side constituting a stop for the lever adjacent said position and the root of the slot at the opposite side spaced from the lever constituting a stop for release movement of the lever. 15

2. The structure of claim 2, said lever having two arms, one having a hook on the lower side thereof, a cam face exteriorly of said hook inclined upwardly and outwardly therefrom, the oppositely extended arm being provided with a 25 spring-engaging notch in the lower side thereof and having operating portion at its outer part, a flat longitudinally compressible leaf spring within the standard, one end of which rests in the said spring engaging notch, the other end 30 of the spring seated inside said standard.

HARRY W. TITUS.
